CARBURETOR

Lester H. Messinger, Jr., Trumbull, Conn., assignor to Messinger Devices, Incorporated, Bridgeport, Conn., a corporation of Connecticut

Application December 16, 1936, Serial No. 116,070

3 Claims. (CL 261—34)

This invention relates to new and useful improvements in carburetors.

The invention provides means whereby the fuel discharged by a vacuum operated accelerator pump of a carburetor is forced by the pump into a receptacle and is drawn from said receptacle into an engine fed by the carburetor only while the carburetor throttle valve is open and the engine is operating.

10 The objects and advantages of the invention will become apparent from a consideration of the following detailed description taken in connection with the accompanying drawing wherein there is shown a satisfactory embodiment of the invention. However, it is to be understood that the invention is not limited to the details disclosed but includes all such variations and modifications as fall within the spirit of the invention and the scope of the appended claims.

20 In the drawing:

Fig. 1 is a view partly in side elevation and partly in section showing a carburetor embodying the invention;

Fig. 2 is a top plan view with parts broken away and showing the invention;

Fig. 3 is a detail sectional view showing the carburetor fuel pump in discharged position;

Fig. 4 is a plan view of a receptacle employed;

Fig. 5 is a vertical sectional view through such receptacle;

Fig. 6 is a detail sectional view through the economizer valve; and

Fig. 7 is a detail sectional view through a check valve.

35 Referring in detail to the drawing a carburetor of the down draft type is shown and the same comprises upper and lower sections 10 and 11 secured together by screws 12. Within the carburetor is any or the usual venturi 13 located above the throttle valve 14. In the float chamber 15 the fuel is maintained at the level indicated by the line 16, being controlled by a float (not shown) regulating the admission of gasoline or other fuel from any source through a connection 17.

40 The carburetor includes a vacuum operated fuel pump generally designated 18 and comprising a chamber 19 constituting the pump cylinder. Within said cylinder there is arranged pistons 20 and 21 connected by a rod 22 about which is coiled a spring 23 bearing at its respective ends against the piston 20 and a collar 24. In Fig. 1 spring 23 is compressed and the pistons 20 and 21 are in the positions occupied by them when the 45 pump is loaded while in Fig. 3 the pump is in

discharged position. The spring 23 constantly tends to maintain the pistons in the positions of Fig. 3 and to return them to such positions when moved therefrom.

Through a cross passage 25 the upper end of the pump cylinder 18 is placed in communication with the upper end of a vertical passage 26 which through a lateral branch 27 communicates with the fuel passage 28 below the throttle valve 14. Through the described passages suction from the engine, while the latter is operating, will serve to exhaust air from above the piston 21 and the piston assembly, including pistons 20 and 21 and the rod 22, will be drawn upwardly compressing the spring 23 bringing about loading of the pump. That is the suction moves the pump to the position of Fig. 1.

5 A lateral passage 29 from the lower end of the pump cylinder communicates through a one way valve 30 with the float chamber 15. Valve 20 30 (see Fig. 7) is a flap valve including a valve proper designated 31 opening downwardly and normally open to permit of the flow of fuel from the float chamber into the cylinder 18. On downward movement of the piston 20 under the urging of the spring 23 pressure is applied to the fuel in chamber or cylinder 18 and the passage 29 and valve 31 moves upwardly against its seat 32 preventing the fuel being forced back into the float chamber.

25 Below the pump cylinder is a well 33 communicating by way of a passage 34 with a fuel jet or nozzle 35 which in the present case is the power jet of the carburetor discharging in a small venturi 13a. An economizer valve 36 is arranged to close off communication between the jet 35 and the pump when the latter is in loaded position. This valve includes a stem 37 carrying a valve proper 38 (see Fig. 6) and the lower end portion of the stem is guided in a spider 39. Between the spider and the valve 38 a spring 40 is disposed about the stem 37 and under normal conditions is effective to maintain the valve on its seat. The arrangement is such that if there is no other escape for fuel as the pump discharges then the valve 38 is forced open and the fuel discharged through the nozzle or jet 35.

30 Arranged at one side of the body of the carburetor is a small tank or receptacle 41 adapted to receive fuel discharged by the pump as will later be set forth. While the tank or receptacle is shown outside the body of the carburetor it will become apparent as the description proceeds that it might equally well comprise a chamber formed within the body of the carburetor.

Therefore, while in subsequent portions of the specification and in the claims the part 41 is referred to as a "receptacle" it is to be understood that such word is used as including a separate 5 tank as shown or a compartment or chamber formed in the main body of the carburetor or at any other convenient location.

Receptacle 41 is shown as a flat, generally rectangular device although the particular shape is 10 not controlling. It includes a body portion 42 and a top or cover 43 secured in place as by screws 44. By means of a partition 45 the interior of the body 42 is divided into chambers 46 and 47 of which the latter is shown somewhat 15 larger than the former. Threaded into the upper end of chamber 46 is a plug 48 having metered orifice 49 therethrough. The upper surface of the plug is flush with the upper end of the body but the top 43 is hollow in its under side 20 so that the chambers 46 and 47 are in communication through the orifice 49.

Receptacle body 42 is provided with an inlet 25 50 entering the lower end portion of the chamber 46 and with an outlet 51 from the lower end portion of chamber 47. Into these openings are threaded elbows 52 and 53 respectively. On one face of the body 42 is a boss 54 having a threaded stud 55 projecting therefrom. A drilled hole 56 through the stud communicates with the interior of the body, entering the upper portion 30 of chamber 47. If desired a metering plug 57 is threaded into the elbow 53 so as to be removable and replaceable should an orifice of a different size be desired.

The passage 29 communicates with a well 58 at the lower side of valve 30 and also communicating with the well, being secured by a fitting 59, is a tube 60. Such tube having its other end attached to the elbow 52 by a fitting 61 places the well in communication with the lower end portion of the chamber 46. Thus the chamber 46 is placed in communication with the float chamber 15 through the valve 30 and with the pump through the lateral passage 29. When the piston 20 is in its upper position the pump is 45 loaded with fuel drawn from the float chamber through the valve 30.

Thereafter on the suction or vacuum being reduced the spring 23 acts and the piston 20 descends to discharge the pump. At this time the valve 36 is closed and the pressure on the fuel forces valve 30 closed and the fuel is discharged by the pump through the tube 60. Sufficient pressure to force open the valve 36 is not generated and such valve remains closed until the stem 37 is engaged by the piston 20 as in Fig. 3 when the valve is forced and held open until the piston is again moved upwardly to load the pump.

Heretofore in carburetors of the type shown 60 the pump 18 discharged only through the nozzle 35. The arrangement was such that the pump was operated to loaded position while there was suction in the engine equipped with the carburetor and then on reduction of the suction or 65 vacuum as by opening of the throttle valve 14 the spring 23 of the pump would act to discharge it and the fuel would be forced through the nozzle 35.

With such an arrangement the pump would 70 discharge the fuel through nozzle 35 when the engine ignition was cut off and the engine stopped and such discharged fuel would simply run into the intake manifold and then into the engine when not needed. Also if the engine was equipped with an air inlet valve as shown in my 75

Patent 2,017,914 of October 22, 1935 the pump if in loaded position would discharge through nozzle 35 each time the valve opened at which times it is desirable that no fuel be fed to the engine. To overcome these difficulties and prevent waste 5 of fuel I provide the receptacle 41 and the connections thereto so that at each discharge of the pump the fuel passes to the receptacle and is taken therefrom at such times as the fuel is required by and in accordance with the air entering 10 the engine. That is the fuel is not squirted into the intake by the pump regardless of the air stream but is sucked into the carburetor and thence the engine in proportion to the air entering 15 the engine.

A tube 62 communicates with the lower portion of the chamber 47 being attached at one end to the elbow 53 by means of a fitting 63. Such tube is attached to a wall of the fuel passage 28 by a fitting 64 and extending through 20 such fitting and wall has its other end projecting through the venturi 13 forming a nozzle 65.

The receptacle 41 is mounted on the carburetor by passing the stud 55 through a drilled hole in the carburetor wall so as to dispose an end of 25 the stud in the upper portion of the float chamber 15. Then a nut 66 is threaded onto the stud to clamp a portion of the carburetor wall between the nut and the boss 54 whereby to secure the receptacle to the carburetor. Thereafter an 30 opening 67 is drilled through the nut and into the drilled opening 56 through the stud. Thus the upper portion of the chamber 47 is placed in communication with the carburetor float chamber 15 above the float level. 35

Obviously fuel from the float chamber of the carburetor flows into the receptacle chamber 46 until the level of fuel in chamber 46 is the same as that in chamber 15. Thereafter as additional fuel is forced into chamber 46 on discharge of 40 the pump it may flow through the orifice 49 and over the partition 45 into the chamber 47. Such fuel remains in chamber 47 while the engine throttle valve is closed or while the air inlet valve of my patent above referred to is 45 open. Assuming such air valve to be closed or absent from the engine, on opening of the throttle valve while the engine is operating there is an increase in the suction or degree of vacuum in the venturi of the carburetor and fuel is drawn 50 from the chamber 47 through the tube 62 into the engine. As the engine operates under conditions causing a high degree of vacuum in the Venturi portion of the carburetor fuel is drawn through the tube 62 until the supply in chamber 55 47 is exhausted but the engine cannot draw fuel from the chamber 46.

The capacity of the chamber 46 is such that as the pump is drawn to loaded position should the valve 30 not release the fuel as fast as the pump requires it the additional fuel will be taken from the chamber 46 to satisfy the requirements of the pump. That is during operation of the engine the chamber 46 remains full and its capacity 60 is such that as the pump moves to loaded position it cannot exhaust the fuel from the chamber and so the pump will always get a full load and will not under any circumstances draw air instead of fuel. It is to be understood that should the pump be partly loaded with air a "flat spot" in the operation of the engine will occur when the throttle is again advanced as the discharge will 65 not be of fuel alone. The chamber 47 is of such capacity that in its portion below the level of 70 75

nozzle 65 it may contain several discharges of the pump 18.

Hole 67 has its upper end above the fuel level in the float chamber. Owing to the presence of this hole and the hole 56 which connects it to the interior of chamber 47, when the fuel is exhausted from such chamber, air is drawn through the tube 62 and nozzle 65 and a siphonic action cannot be set up through the tube 62, receptacle 41 and tube 60 to the float chamber of the carburetor. Since air may only be drawn through tube 62 from the source and in the manner specified it will be clear that only air which has passed through an air cleaner will be fed into the engine as all air for the latter passes through a cleaner as it enters the carburetor. As the upper end of the hole 67 is just under the dividing line between the upper and lower sections 10 and 11 of the carburetor it will be apparent that the fuel in the carburetor will never rise to such a level as to cover the opening and there will be no siphoning of fuel direct from the float chamber into the engine through the stud 55, chamber 47 and tube 62.

Having thus set forth the nature of my invention, what I claim is:—

1. In a carburetor including a venturi, a fuel chamber, a nozzle in the venturi, a pump communicating with said fuel chamber and including a vacuum operated means to move it to loaded position and spring means to operate it to discharge fuel on reduction of vacuum on said means, a receptacle, a passage connecting the discharge of the pump with the upper end portion of the receptacle whereby on each discharge of the pump fuel is delivered to the receptacle, said passage communicating with said fuel chamber whereby to maintain the fuel in the passage at the level of the fuel in the chamber, said passage below the level of fuel therein having a greater cubic capacity than said pump whereby said pump in its movements to loaded position cannot exhaust the fuel from said passage and hence is prevented from drawing air, and a passage connecting the lower end portion of the receptacle with said nozzle for the passage of fuel from the receptacle to an engine fed by the carburetor.

2. An attachment for a carburetor including a throttle, a fuel chamber, a fuel pump adapted to be operated to loaded position by vacuum, and a spring means to operate the pump to discharged position, a receptacle at the outer side of said carburetor, means providing a passage at the

outer side of said carburetor and connected with said fuel chamber whereby the level of fuel in said passage is the same as that in the fuel chamber, said passage also connected with said receptacle and said pump whereby at each discharge of the pump fuel is forced through said passage into the receptacle, said passage below the level of fuel therein having a greater cubic capacity than said pump whereby said pump in its movements to loaded position cannot exhaust the fuel from the said passage and hence is prevented from drawing air, an outlet passage from the receptacle into the carburetor and through which fuel is drawn into an engine fed by the carburetor on opening of said throttle while the engine is operating, a hollow bolt secured to said receptacle and passing through a wall of the carburetor and securing the receptacle to the carburetor, and said hollow bolt providing a passage communicating the upper portion of said receptacle with the interior of the carburetor above the liquid level therein whereby to prevent setting up of a siphonic action through the receptacle and whereby to balance the air pressure in the receptacle and in the carburetor.

3. In a carburetor, a fuel pump adapted to be operated to charged position by vacuum and other means to operate the pump to cause it to discharge fuel, a receptacle of a capacity to contain several complete discharges of said pump, means connecting the receptacle with the carburetor for the passage of fuel therethrough from the receptacle to an engine fed by the carburetor, said connecting means and receptacle arranged and constructed whereby fuel is drawn into the engine from the receptacle only when the engine is exerting a suction pressure on the carburetor, and means providing a passage between the pump and receptacle whereby on reduction of vacuum on the pump all fuel discharged thereby is delivered to and retained by said receptacle whereby to prevent waste of fuel when the vacuum pump discharges and there is no suction on said carburetor and whereby to have such fuel available to the engine through said connecting means on reestablishment of suction in the carburetor, said passage connected with the fuel chamber of the carburetor whereby to contain fuel to the level of the liquid fuel in the carburetor, and said passage in its portion below said fuel level having a cubic capacity greater than that of the pump whereby the pump as it charges may not draw air from said passage.

LESTER H. MESSINGER, JR.
